UNITED STATES PATENT OFFICE.

JOSEPH ALGER, OF BROCKTON, MASSACHUSETTS, ASSIGNOR TO HIMSELF
AND ARTHUR H. ALGER, JOINTLY, OF BROCKTON, MASSACHUSETTS.

BOX-COVERING MACHINE.

No. 851,052.

Specification of Letters Patent.

Patented April 23, 1907.

Application filed May 10, 1904. Serial No. 207,234.

To all whom it may concern:

Be it known that I, JOSEPH ALGER, a citizen of the United States, residing at Brockton, in the county of Plymouth and Commonwealth of Massachusetts, have invented certain new and useful Improvements in Box-Covering Machines, of which the following is a specification.

This invention relates to machines for covering paper boxes, and particularly to that class of machines which folds and pastes about the box a paper blank attached to its bottom.

It has been difficult heretofore with any of the machines in use to apply the paper neatly and evenly, and in feeding these boxes to the machine it has been difficult to secure accuracy of location of the box relative to the folding members, which is necessary to prevent irregularity and defects in the folding of the paper about the box. In the manufacture, also, of the type of box known as the "package end" it is desirable to have the covering-paper folded with a round turn instead of being sharply creased at the edge, this being to give the padded effect of a package, which, as the name indicates, it is sought to have the box resemble. The above features are gained by the use of certain holding and folding members and the coöperation of certain parts, which will be more fully described later.

In the drawings, in which like letters of reference indicate corresponding parts throughout, Figure 1 is a general view of my machine. Fig. 2 is a diagrammatical section on the line 2 2, Fig. 4, with the folder open. Fig. 3 is a similar view with the folder closed. Fig. 4 is a plan view showing the top of the machine, and Fig. 5 is a detail of a modification of the end-turner.

A is a box-support having hinged thereto side-folders B and end-folders B', which carry edge-turners C.

D D' are slides which are reciprocated on a rod E by treadles F F', respectively. G are links connecting these heads with the side-folders, so that the latter are swung up against the box as the slides are raised.

H H' are links normally held in a bent position when the side-folders are open by

the spring h and which connect the link G with the edge-turners C.

h' is a projection carried by the slides D D' and adapted to engage the cross-bar h² of the link H as the slide rises and the link G swings in, so that as this motion continues the bent links are straightened and act as toggles to tip the edge-turners C over the edge of the box.

I are end-turners mounted upon the side-turners for bringing the covering-paper about the end of the box and to produce the necessary fold in the package end. These turners are pivoted at i, so as to rotate, and thus avoid any danger of drawing or pucker-
ing the paper as it is swung into place.

In the form shown in Fig. 1 the turners are segmental and are controlled by spring-links i', which tend to move the turners slightly on their pivots relative to the side-turners C as they are swung up and also to tip the turners I against the ends of the box as the link G is swung up. This movement is due to the fact that the spring-links i' diverge from the cross-bar g and are subjected to a wedging action as the link G swings up to close the folder.

In the modification shown in Fig. 5 these end - turners are shown as simple disks mounted on the side-folders, so as to be free to rotate. In this case no wedging action is obtained, and the only motion of the turner itself is a slight revolution if there is any tendency on the part of the paper to pucker or stick.

Mounted upon the block A is a holder K, which consists of a body portion and side portions, but being open at each end. The sides of the holder K is slightly smaller than the sides of the box to be operated upon, so that when the side-folder is swung up the edge-turner and end-folder will have room to clear the same. This holder is preferably made of sheet metal and may be easily made of any size desired to suit any box to be covered and is removably secured to the block A by screws. L is a belt, of leather or canvas, also attached to the block A and preferably located between it and the holder K.

M are bent arms carried by the end-folders, which hold the belt L yieldingly extended by

the springs *m* and slightly in advance of the end-folder. The belt is of just sufficient height to allow the edge-turner *C* on the end-folder to pass over it in turning the edge of the covering-sheet over the edge of the box. 5 The slides *D D'* are held lowered, and the side-folders are therefore held normally open by the weight of said slides which are raised to operate the parts by the treadles *F F'*. 10 The operation of the machine is as follows: A box having applied to its bottom a covering-sheet is set into the holder, by which act the covering-paper for the side of the box is turned up, but extends above the edge of the holder and the box. By depressing the 15 treadle *F* the side-folder is then swung into place against the outside of the holder, the edge-turner passing over said holder and box to turn the edge of the covering-sheet in on the inner surface of the box and press it firmly in place, as shown in Fig. 3. The disk *I* in the meantime has folded the covering-sheet about the corner of the box and made the necessary crease for the fold to be made 20 by the end-folder. The treadle *F'* is now depressed and the end-folders swung up into place. As these folders rise the belt *L*, travelling in advance thereof, first meets the end section of the covering-paper and brings it up 25 to the box with a loose turn, due to its yielding nature. After the belt has thus located the end portion of the covering-paper against the box the end-folder is brought up closely against the box, and the edge-turner carried 30 thereby binds the paper over the edge and presses it in place, as heretofore described in connection with Fig. 3. In the folding of the paper against the box the belt draws up the paper smoothly and keeps it smoothly extended 35 in spite of the swinging action of the side-folders, which, if acting directly on the paper, would have a tendency to crumple it and leave it wrinkled. Although shown as applied to a machine for covering package-end boxes, 40 this flexible belt may be applied to any type and is of the greatest importance in all machines using swinging side-folders. The head *D'* then falls by its own weight upon the release of the treadle *F'*, and the folder opens to 45 release the box. The connection of the side and end folders are the same, as are also the edge-turners, mounted upon these members; but the side-folders carry the end-turners *I* and are not connected with the belt, while the 50 end-turners *B'* have no folders *I*, but carry the ends of the belt *L*. 55

The belt *L* may be of any suitable construction and material or may be made in the form of a yielding section on the folder; but I 60 prefer the belt form, as it is cheaper to make, more easily replaced, and adapted to various sizes and types of work. The holder also may be of any desired form and may be made with mere fingers instead of a solid side, as shown. Various other modifications

and substitutions of parts may also be made without departing from the spirit of my invention.

What I therefore claim, and desire to secure by Letters Patent, is—

1. In a machine for covering paper boxes, folding means, means for drawing the covering-paper about the box in advance of said folding means, said means being flexible throughout.

2. A machine for covering paper boxes, having swinging folding means and flexible means for drawing up the paper in place in advance of said folding means.

3. In a machine for covering paper boxes, the combination of swinging folding members, and flexible means mounted in advance of the same to locate the covering-paper in place.

4. In a machine for covering paper boxes, the combination of swinging folding members, a flexible web carried by said members and mounted in advance of the same to locate the covering-sheet in place.

5. In a machine for covering paper boxes, side-folding members and end-folding members, said end-folding members carrying in advance thereof a flexible web to locate the paper in place.

6. In a machine for covering paper boxes, the combination of means for supporting a box and covering-paper, a folder for folding the paper about the box, a flexible sheet for drawing up the covering-paper, and means for holding said flexible sheet yieldingly stretched between the box and folder.

7. In a machine for covering paper boxes, a rigid holder having bottom and side members but open at each end, folders mounted to swing relatively thereto, and edge-turning members on said folders to turn the covering-paper on the inside of the box.

8. In a machine for covering paper boxes, a support for the bottom of the box, side-folding members hinged thereto, a vertically-movable frame, links connecting said frame to said side-folders, edge-turners pivoted to said side-folders, double links connecting said edge-turners and said first-mentioned links and a cam for straightening said double links to tip the edge-turners.

9. In a machine for covering paper boxes, the combination of a holder, folding members hinged to swing relatively thereto and flexible means for drawing up the covering-paper in advance of said folding members.

10. In a machine for covering-paper boxes, a holder having bottom and side portions but open at each end, folders mounted to swing relatively thereto, edge-turning members on said folders to turn the covering-paper on the inside of the box, and flexible means for drawing up the covering-paper in advance of said folding members.

11. In a machine for covering paper boxes,

a support for the bottom of the box-side-folding members hinged thereto, a vertically-movable frame, links connecting said frame and said side-folders, edge-turners pivoted to said side-folders, bent links connecting said edge-turners and said first-mentioned links, a stud on the frame for straightening said bent links to tip the edge-turners, and flexible means to locate the covering-paper car-

ried by the folding members in advance thereof.

In testimony whereof I affix my signature in presence of two witnesses:

JOSEPH ALGER.
